SCISSORS SHARPENING DEVICE

Martial J. Robitaille, Cleveland, Ohio

Application March 9, 1949, Serial No. 80,527

8 Claims. (Cl. 76—89.2)

1

This invention relates in general to devices for sharpening cutting tools, and, more particularly, to scissors sharpening devices of the type embodying as sharpening means a round, tempered and preferably highly polished steel pin. Scissors sharpening devices of this type, which have their steel or sharpening pin rigidly mounted in a fixture or handle member, can effect proper sharpening of bevel-edged scissors blades only when the taper of the bevel edged blades extends parallel to the longitudinal axis of the steel or cutting pin so as to provide a line contact of the bevel-edged blades with the steel pin, which line contact is highly important for proper and uniform sharpening of the scissors blades; however, such line contact cannot be effected with present day scissors sharpening devices which do not compensate for substantial variances of the taper angle of beveled edges of blades of scissors of various makes and sizes.

The general object of the present invention is the provision of a simple, neat and inexpensive scissors sharpening device having a shiftably supported sharpening steel pin adapted to be automatically aligned during scissors sharpening operations with the scissors blade shearing angle of the scissors to be sharpened, so as to effect in scissors sharpening operations a line contact of the tapered cutting edges of the scissors blades with the sharpening steel pin of the scissors sharpening device.

Another object of the invention is the provision of a simple, neat and inexpensive scissors sharpening device having a sharpening steel pin mounted to freely rotate in a plane through the longitudinal axis of the pin around an axis extended through said pin, midway thereof, and in rectangular relation to said plane, the sharpening steel pin being adapted to be automatically rotated during scissors sharpening operations so as to effect a line contact of the tapered cutting edges of the scissors blades with the sharpening steel pin of the scissors sharpening device.

A further object of the invention is the provision of a simple, neat and inexpensive scissors sharpening device of the type described, in which the sharpening steel pin supports at its opposite ends curved shoe members and in which these shoe members are guided in curved guide ways of a fixture or handle member supporting said sharpening steel pin to permit in scissors sharpening operations automatic shifting of the pin and effect a line contact of the tapered cutting edges of scissors to be sharpened with the sharpening steel pin of the device.

2

The above and additional objects and novel features of construction, combination and relations of parts by which the objects in view have been attained, will appear and are set forth in detail in the course of the following specification.

The drawing accompanying and forming part of the specification illustrates a certain practical embodiment of the invention, but it will be apparent as the specification proceeds that the structure may be modified and changed in various ways without departure from the true spirit and broad scope of the invention.

In the drawing:

Fig. 1 is a front view of a scissors sharpening device constructed in accordance with the invention;

Fig. 2 is a side view of the device shown in Fig. 1 with a pair of scissors positioned to be sharpened by the device;

Fig. 3 is an enlarged fragmentary transversal sectional view through the device, the section being taken on line 3—3 of Fig. 2;

Fig. 4 is a cross-sectional view partly in elevation taken on line 4—4 of Fig. 3; and

Fig. 5 is a perspective view of the sharpening steel member of the device.

Referring now more in detail to the exemplified form of the invention shown in the drawing, reference numeral 2 denotes a scissors sharpening device embodying a support member 3 and a steel pin member 4 supported thereby. The support member 3 includes a body portion 5, the top end portion of which is shaped to form a hand grip 6, and a bar member 7 attached to one side of body portion 5 by screws 8. The main body portion and the bar member have their opposed faces recessed so as to form support member 3 with an elongated, vertically arranged slot 9. In addition main body 5 and bar member 7 have their opposed faces centrally grooved with sectional circular grooves to provide said body portion and bar member with sectional circular channels 10 and 11, rotatably supporting and guiding the steel pin member 4 so as to permit its rotation in a plane through the axis of the sharpening pin member around an axis extended through said pin member and rectangularly related to said plane.

To facilitate rotation of the sharpening pin member 4 in the supporting and guiding channels 10 and 11, such pin member has attached to its opposite ends sectional cylindrical shoe members 12 and 14 which are sized and curved to fit channels 10 and 11 to guide the sharpening pin member during sharpening operations, and

permit its automatic rotation by the scissors blades, so as to effect a line contact of the tapered cutting edges of the scissors blades with the sharpening pin.

Preferably support member 3 has secured to its bottom end a rubber strip 15 to facilitate proper support of the scissors sharpening device during scissors sharpening operations.

In sharpening operations when the device is supported on a desk or the like on rubber strip 15 and held in vertical position, the scissors in slightly opened up position are extended through vertical slot 9, so that the blades extend above and below sharpening pin member 4. Then the blades are gently passed over the sharpening pin with forward and backward movements of the scissors and opening and closing movements of the blades. Such movements of the scissors and blades effect automatic rotation of sharpening pin member 4 until such member is in line contact with the tapered cutting edges of the blades, the position necessary to produce a smooth and sharp cutting or shearing edge on the scissors blades.

Having thus described my invention, what I claim is:

1. A scissors sharpening device comprising a supporting member having an elongated slot axially thereof, an elongated sharpening pin member, and supporting means for said pin member arranged to permit rotation of said pin member in said supporting member in a plane which includes the longitudinal axis of said pin member and around an axis extending through the center of the longitudinal axis of said pin member and in perpendicular relationship to said plane.

2. A scissors sharpening device comprising a supporting member having an elongated slot axially thereof, an elongated sharpening pin member, and supporting means for said pin member to freely, floatingly support same for movements in a plane which includes the longitudinal axis of said pin member and around an axis extending through the center of the longitudinal axis of said pin member and in perpendicular relationship to said plane.

3. A scissors sharpening device comprising a supporting member having an elongated slot axially thereof, an elongated sharpening pin member, and a sectional cylindrical guideway freely, shiftably supporting said sharpening pin member, said sectional cylindrical guideway being arranged in said supporting member and intersecting said slot midway thereof in symmetrical relation with respect thereto, to permit proper automatic positioning of the sharpening pin during scissors sharpening operations.

4. A scissors sharpening device comprising an elongated supporting member having a handle at one end and a friction member at its other end, an elongated slot formed in said elongated member longitudinally thereof, a sharpening pin member shiftably supported by said supporting member, and guideways for said pin member

arranged in said supporting member and to support the pin to intersect said elongated slot in symmetrical relation with respect thereto.

5. A scissors sharpening device comprising an elongated supporting member having a slot longitudinally thereof, a sharpening pin member shiftably supported by said supporting member, and cooperating means on said supporting member and sharpening pin member to support the same in all possible positions in intersecting symmetrical relation with respect to the slot in said supporting member.

6. A scissors sharpening device comprising an elongated supporting member having an elongated slot longitudinally thereof, and a sharpening pin member shiftably supported at its opposite ends in said supporting member, said supporting member including sectional cylindrical recesses adjacent to said slot for the opposite ends of said sharpening pin member arranged and sized to permit free shifting of said sharpening member in intersecting symmetrical relation with respect to said slot.

7. A scissors sharpening device comprising an elongated supporting member having an elongated slot longitudinally thereof, and a sharpening pin member shiftably supported at its opposite ends in said supporting member, said supporting member having sectional cylindrical recesses adjacent to said slot arranged in symmetrical relation with respect thereto, and said sharpening pin member including mounted on its opposite ends shoe members fitting said cylindrical recesses and seated therein to permit free shifting of said sharpening member in symmetrical relation with respect to said slot.

8. In a scissors sharpening device including a supporting member and a sharpening pin member, an elongated slot in said supporting member, and shiftable guiding and supporting means for said sharpening member arranged to permit shifting of said sharpening pin symmetrically with respect to said slot.
